CRANKSHAFT TWISTER

Arthur T. Hunt, Fort Wayne, Ind., assignor to
 International Harvester Company, a corpora-
 tion of New Jersey

Application April 6, 1931, Serial No. 527,878

11 Claims. (Cl. 29—6)

In the manufacture of crank shafts for internal combustion engines, it is now common practice to forge a shaft blank having cranks in parallel or opposite position with the blank formed flat. To complete the shaft, the blank is heated and locked into dies of a so-called crank shaft twisting machine, the function of the machine being to twist the cranks, or certain of them, to the relative angular positions which they must assume in a finished crank shaft.

This invention relates to an improved crank shaft twisting machine, and the objects thereof are to provide a novel form of die-holding twisting elements; to provide improved means for rocking said elements about fixed, aligned centers; to provide hold down means of novel construction for such elements to insure their proper turning movement about such aligned centers; to provide a simplified and improved driving mechanism for power actuating said rockable elements; and, lastly, generally to improve forging machines of this character.

Other important objects of the invention will appear to those skilled in this art as the disclosure is more fully made hereinafter.

The illustrative embodiment of the machine herein chosen for purposes of the disclosure will be for twisting crank shafts of the six-cylinder, seven bearing variety as used in a six-cylinder internal combustion engine.

Briefly, the embodiment of the invention thus chosen involves a base carrying spaced brackets, certain of which serve to mount non-twisting clamps to lock certain portions of the crank shaft blank, while the remaining brackets carry arcuate roller tracks including rollers which serve to hold down half-circle rocker elements carrying clamps for holding the crank portions of the blank to be twisted to offset angular positions. These rocker elements all rock about non-physical, or imaginary points of turning, such centers all being aligned to produce an accurately aligned crank shaft. These movable rocker twisting elements are power actuated by means comprising pitmen driven from an eccentric mechanism. So much will suffice for the present in portraying a general idea of the structure presently to be described in complete detail.

In the accompanying sheets of drawings,—

Figure 1 is a general end view of the complete machine with a shaft blank locked therein ready for initiation of the twisting operation;

Figure 2 is another end view of the machine, showing the relative positions assumed by the parts as the twisting action takes place;

Figure 3 is a general plan view of the machine, as viewed in Figure 1;

Figure 4 is a longitudinal sectional view as seen along the line 4—4 shown in Figure 1, when viewed in the direction indicated by the arrows;

Figure 5 is a detail sectional view through a twisting element and a portion of the machine as viewed along the line 5—5 appearing in Figure 3, when looking in the indicated direction;

Figures 6 and 7 are, respectively, side and end elevational views of a twisting rocker element;

Figure 8 is a plan view of the power connections for driving the machine, including the starting and stopping control therefor;

Figures 9 and 10 are, respectively, plan and end views of the blank prior to twisting the same; and,

Figures 11 and 12 are, respectively, plan and end views of the completed, or twisted, crank shaft.

In mounting the machine, the floor of a forge shop is provided with a suitable bed 15, as shown in Figure 3. Formed as a part of the bed is the base 16 of the machine, which in practice will be raised to provide a horizontal table 17, as best appears in Figures 1 and 4. Said table 17 carries in lengthwise alignment four vertically disposed, rectangularly shaped, wall-like brackets 18, 19, 20 and 21, said brackets being spaced apart and disposed transversely in parallelism with each other. The brackets 18 and 21 constitute end brackets, while the brackets 19 and 20 constitute intermediately disposed brackets which may comprise, as shown, a unitary casting. See Figure 4.

Formed longitudinally through the brackets 18, 19, 20 and 21 in alignment are bores that receive roller shafts 23 of short length in such a manner that each bracket journals one of said shafts. These shafts 23 in the end brackets 18 and 21 carry enlarged rollers 24 which fit in pockets 22 formed in the end brackets and project laterally a distance of the inner faces of said end brackets 18 and 21. Thus, it will be seen that the shafts 23 of the end brackets have a roller 24 at one end only, whereas the shafts 23 carried in the intermediate brackets 19 and 20 have such rollers 24 at each end to fit in the pockets 22 on each face of said intermediate brackets 19 and 20. The shafts 23 and rollers 24 so far described are on a longitudinal axis passed through the bottom-most of each of the pockets 22 in the respective brackets. From Figures 1 and 2 it will be noted that the two upper corners of each bracket carry additional shafts 23 and rollers 24 of the

5

55

same kind, said rollers all being located on fixed axes in the respective roller carrying pockets 22. Thus, it is clear that there are three pockets 22 formed on each bracket face, said pockets carrying three spaced rollers 24 in the manner shown in Figures 1 and 2.

These rollers 24 serve as bearings and hold down means for the twisting rocker elements now to be described. Such rocker elements are 10 three in number, there being two at the ends and one in the middle, as viewed in Figure 4. A detail showing of the two end twisting rocker elements appears in Figures 6 and 7, where it will be seen that each comprises two vertical plates 25, each 15 of a shape approximating the segment of a half-circle. These two plates are separated by a spacer 26, the plates and spacers being suitably bolted together to form a unitary rocker element having a flat upper surface along the diameter of the 20 segment, as shown in Figure 6. Each outside face of the plates 25 is formed with a half-circle groove or track 27 in registration or alignment with the pockets 22 in the adjoining face of the brackets 18, 19, as the case may be. The rollers 25 25 fit into both track portions 27 and pockets 22, and so it is that the end twisting rocker elements are mounted on the brackets 18, 19 and 20, 21 for rocking movement in a circular path, and on the rollers 24 serving as bearings therefor, and 30 further because the rollers are locked in the pockets 22 of the stationary brackets, a hold-down action is exerted by the rollers on these rocker elements, so that in their movements they turn about an imaginary fixed axis of rotation.

The central or intermediate twisting rocker element is similar, but of a somewhat modified construction, the same comprising, as best appears from Figure 4, a unitary member having two spaced vertical plates 28 which also are 40 approximately shaped like the segment of a half-circle. These plates are connected by a diametric flat top 29, and each outer face of said plates is formed with a roller track in half-circle curvature of the kind heretofore described, said tracks 45 receiving the two center rollers 24 to support said twisting element 28, 29 in its rocking movement, and also to hold said twisting member down, to insure its movement about a fixed, imaginary turning point as described in connection 50 with the other twister rocker elements 25.

Normally, the flat top sides of these rockable twister elements all lie flush with the top edges of the four brackets 18-21, inclusive, as shown in Figure 1. All of these brackets are cross-braced and securely held on the base 17 by an angle beam 30.

The two end twisting rocker elements 25, after the fashion shown in Figures 6 and 7, each have secured to their top sides, a lower clamp element 31 of a vise-fixture, which also includes a complementary, hinged, upper part 32 (see Figure 5). These two vise-fixtures are designed to clamp certain crank portions of the shaft blank. These fixtures include clamps 33 combined with 65 conventional hand operated cam lever locks 34, whereby the blank may be securely held at the particular points mentioned. The intermediate rocker element 28 has similarly anchored to its top 29, a duplex vise-fixture having a lower jaw part 35 (see Figures 2 and 4) and a hinged upper jaw part 36, the two jaw parts being likewise locked together to clamp two intermediate crank portions of the blank, by means of a single, hand operated cam lever lock handle 37.

Carried on the brackets 19 and 20 are similar,

but non-twisting vise-fixtures 38 and 39, respectively, for locking two additional portions of the blank. These fixtures 38, 39 have cam lever locks 40 and 41 of the kind previously described.

Conventional air or steam operated piston cylinders are provided as additional means to hold these several vise-fixtures positively closed. Accordingly, the rocker element 25 at one end of the machine, as appears in Figure 1, carries a support 42 for pivotally mounting such a cylinder 10 43 having a push-pull rod 44 connected by a block 45. Likewise, the rocker element 25 at the other end of the machine is provided with a support 46, pivotally carrying an air or steam cylinder 47 having a push-pull rod 48 connected by a block 15 49 to the upper jaw 32 of the vise-fixture on the rocker 25 mentioned. See also Figure 5.

At the other side of the machine, the two intermediate brackets 19 and 20, respectively, carry supports 50, 51. The support 50 pivotally mounts 20 another cylinder 52 having a push-pull rod 53 connected by block 54 to the upper jaw of vise-fixture 38, while the support 51 pivotally mounts a cylinder 55 having a push-pull rod 56 connected by a block 57 to the upper jaw of the vise-fixture 39.

To one side of the main part of the machine above described, the table 17 carries two spaced, vertical brackets 58, as best shown in Figures 1 and 2. These brackets 58 serve as supports for 20 two vertically disposed A frames 59 spanned by a crosspiece 60, from which is pivotally hung another air or steam cylinder 61 having a push-pull rod 62 connected by a block 63 to the top jaw part of the duplex vise-fixture 36 carried by the 25 intermediate twister rock member 29.

Two coaxially aligned shafts 64 are journaled one each in each bracket 58, said shafts being spaced apart at their inner ends where each carries a large gear 65, said two gears, as shown in 40 Figure 3, being spaced apart and connected by an eccentrically disposed crank pin 66. Journaled on this pin is a pitman 67 having pivotal connection with the intermediate rockable twister element 29. The outer ends of each shaft 64 are 45 provided with cranked ends 68 extending together in the same direction, which is opposite relative to the eccentric crank pin 66. Journaled on the cranks 68 are pitmen 69, one being pivotally connected to the rockable twister element 25 at 50 one end of the machine, while the other pitman is pivotally connected to the rockable twister element 25 at the opposite end of the machine. The spacing apart of the two gears provided a space in which the intermediate pitman 67 plays, said 55 pitman being appropriately connected to the rocker 29 between its spaced sides 28. As for the rockers 25, they too, it will be remembered, are constructed with spaced sides, so that, as shown in Figure 4, the pitmen 69 have room for play. 60 The machine is so constructed that, as the two end pitmen 69 move in one direction, the intermediate pitman 67 moves in an opposite direction. The power connections for driving the gears 65 and cranks 68 will now be described. 65

Carried on any suitable extension 70 of the table 17 (see Figures 1 and 8), is an electric motor 71, the shaft of which is coupled to an in-and-out clutch generally shown at 72, having a shifter lever 73 connected with a horizontal shifter 70 member 74 that is carried slidably in the eye 75 of two end supports 76 connected to the base extension 70, as shown. Continuing with the drive train, the power passes the clutch 72 to a suitable gear reducer 77, from which projects a shaft 78 75

(see Figure 2) carried in journal brackets 79. This shaft 79 carries a wide pinion 80 in mesh with the two large gears 65 heretofore described. A brake 81 is included in the assembly, as shown 5 in Figure 8.

Before describing the operation of the complete machine, it will be well to consider a type of crank shaft that may be twisted by the machine. The blank forging of the shaft has been illustrated in Figures 9 and 10, where it will be seen that the shaft, before twisting, is generally indicated at 82, the same being provided with six cranks, the two center ones of which, indicated at 83, and the cranks at the ends, indicated at 84, 10 all extend in the same direction, while two intermediate cranks 85 are also provided to extend in the opposite direction. These cranks are all of uniform throw and, before twisting, appear flatly disposed, as shown in Figure 10. Preparatory to 15 twisting the cranks, this blank is heated and, while still hot, the same is placed in the vise-fixtures of the machine in the manner best shown in Figures 3 and 4, it being understood that said vise-fixtures comprise upper and lower jaw parts, 20 which have die depressions formed therein to conform to the shape of the cranks in the blank, in the manner well known to this art. The various cam lever locks 34, 37, 40 and 41 are then manually locked. Now, it can be seen that the 25 two end cranks 84 are locked in the vise-fixtures carried by the two end twister rocker elements; the two center cranks 83 are similarly locked in the duplex vise-fixture carried on the center twister rocker element 29; and, lastly, the two intermediate cranks 85 are locked in the two intermediate vise-fixtures 38, 39, which are non-rockable, or fixed, as they are anchored securely and fast to the intermediate frame brackets 19 and 20. Appropriate valve control means, not 30 herein disclosed, will be operated to cause each of the pistons in the cylinders 43, 47, 52, 55 and 61 to push on their respective rods positively to hold the several vise-fixtures closed, in a manner common in this art.

45 The purpose of twisting the cranks obviously is to offset the same relatively to each other to the final finished form which the shaft must assume when installed in a six cylinder internal combustion engine. Accordingly, the lever 73 is actuated by appropriate hand manipulation of the shipper bar 74. Thus, the motor 71 drives the reduction gearing 77, which in turn drives the wide pinion 80 and the two large gears 65 and their two shafts 64. As a result, the cranks 68 50 actuate the pitmen 69 toward the right, as viewed in Figures 3 and 5, to pull the two end rocker elements 25 upwardly through an arc of 120 degrees, causing the two cranks 84 of the shaft blank 82 to be twisted a like amount. At the same time, the eccentric pin 66 drives the pitman 67 in the opposite direction, causing the central twister rocker element 29 to rock upwardly through an arc of 120 degrees and, as a result, the two central cranks 83 become twisted. This 55 relative position of the parts just described is clearly shown in Figure 2. As for the two cranks 85, they are held stationary and thus they too become relatively offset with respect to the other cranks 120 degrees. As all of the air or steam cylinders heretofore described are pivotally mounted, they are always effective to hold the vise-fixtures closed irrespective of the positions assumed by the rocker elements during the twisting operation.

70 75 The stroke of the pitmen 67 and 69 is such that

the rocker elements 25, 28 can only move through their half-circle paths on the roller tracks heretofore described the desired distance necessary to twist the cranks in the shaft blank through the predetermined angular distance of 120 degrees. 5 When the rocker elements have thus reached their maximum point of rocking movement, then the lever 73 will be actuated to stop the drive, whereupon the machine comes to a standstill. The brake 81 can be brought into play to overcome the inertia of the parts. Such control will be by hand, as far as the present disclosure goes, although the same can easily be made automatic, if desired. At this point in the operation, the shaft has been twisted and the machine is out of 10 operation. Thereupon, the operator throws open the several cam lever locks 34, 37, 40 and 41. Next, the machine is again set in operation by means of the lever 73 and simultaneously therewith the valve control for the cylinders 43, 47, 20 25 52, 55 and 61 will be actuated in any appropriate way to reverse the pistons therein to cause the same to open the several vise-fixtures. As the machine has also now been set in operation, the pitmen 67 and 69 are reversed, whereupon the 30 35 rocker elements are returned to their normal or starting positions with the vise-fixtures at this time fully opened and the twisted crank shaft released, to permit removal thereof from the machine. The machine is now ready to receive a new shaft blank and the operation is thus repeated for each shaft to be twisted.

The finished shaft is shown in Figures 11 and 12 and the same reference characters have been applied thereto as were used in Figures 9 and 10. 35

From the above disclosure, it must now be apparent that the rollers 24 provide an anti-friction track for the twister rocking elements and further exert a hold-down action on such rocker elements, thereby insuring that these members always rock 40 about an axis which is coextensive with the axis of the crank shaft in process. These rocker arms accordingly then have no physical, fixed axis, such as a pivot pin, but are instead held down and confined to rocking movement in half-circle 45 paths about aligned, imaginary points or axes. This structure including the pitmen 67 and 69, plus the driving mechanism therefor achieves all of the desirable objects heretofore recited for the invention. 50

It is the intention to cover all changes and modifications of the example herein disclosed, which do not, in material respects, constitute a departure from the invention as defined in the appended claims. 55

What is claimed is:

1. In a machine of the class described, a base, upright brackets carried thereon in spaced relationship, twisting elements rockingly carried between said upright brackets, rollers mounted in the brackets, tracks in the elements to receive the rollers, said rollers holding the elements down for movement about fixed axes, vise-fixtures carried by the twisting elements adapted to receive a crank shaft blank to be twisted, and means for rocking the twisting elements. 60

2. In a machine of the class described, a base, upright brackets carried thereon in spaced relationship, rollers carried in the brackets, half-circle rocker elements provided with half-circle tracks to receive said rollers for rockingly mounting the elements on the brackets, vise-fixtures carried by the rocker elements, said fixtures adapted to clamp a crank shaft blank to be 65 70 75

twisted, and means for rocking the twisting elements.

3. A crank shaft twister comprising, in combination, a base, a plurality of vertically disposed brackets carried by the base in spaced relationship, twister elements between the brackets, rollers between the brackets and twister elements, means for rocking said twister elements, said rollers being mounted on fixed axes in the brackets to carry the twister elements on the brackets and also to exert a hold-down action on the elements to confine them for turning movement about fixed aligned axes, and vise-fixtures carried by the twister elements adapted to receive and clamp a crank shaft blank.

4. A crank shaft twister comprising, in combination, a base, a plurality of vertically disposed longitudinally aligned brackets carried by the base in spaced relationship, twister elements each substantially in the shape of a half-circle arranged one each in the space between two adjoining brackets, half-circle tracks between the twister elements and brackets, rollers in the tracks to mount the twister elements on the brackets and to hold down said elements for movement about fixed, aligned axes, and a vise-fixture carried by each twister element adapted to receive a portion of a crank shaft blank to be twisted.

5. A crank shaft twister comprising, in combination, a base, a plurality of vertically disposed longitudinally aligned brackets carried by the base in spaced relationship, twister elements each substantially in the shape of a half-circle arranged one each in the space between two adjoining brackets, half-circle tracks formed in the twister elements, aligned shafts journaled in the brackets, said shafts carrying rollers arranged in said tracks, said rollers supporting the twister elements and exerting a hold-down action thereon to insure their movement about fixed, aligned centers, means for rocking said twister elements, and vise-fixtures carried by said twister elements adapted to receive and clamp a crank shaft blank to be twisted.

6. A crank shaft twister comprising, in combination, a base, four upright brackets arranged thereon in spaced relation and in longitudinal alignment, twister elements rockingly mounted between said brackets, comprising two end twister elements and an intermediate twister element, means for maintaining said elements for movement about fixed aligned axes, fixtures on the twister elements for clamping a crank shaft blank to be twisted, a pitman for driving the intermediate twister element in one direction, pitmen for simultaneously driving the end twister elements in the opposite direction, a pair of spaced gears having an eccentric pin therebetween for driving the intermediate pitman, means for rotating said pair of gears, and a pair of cranks driven from said gears, said end pitmen connected to be driven from said cranks, said cranks and eccentric pin being opposed whereby the intermediate pitman and end pitmen will be reciprocated in opposite directions.

7. A crank shaft twister comprising, in combination, a base, a pair of spaced brackets vertically disposed on said base, a rockable twister element carried between said brackets, said ele-

ment comprising a unit having two spaced sides, rollers between the said sides and adjoining surfaces of the brackets for carrying and holding said element for movement about a fixed axis, a pitman arranged between the sides of the element, means pivotally connecting the pitman to the element, means for reciprocating the pitman to rock the twister element, and a fixture secured to the element adapted to clamp a portion of the shaft to be twisted.

8. A crank shaft twister comprising, in combination, a base, a plurality of upright brackets carried on the base in spaced relationship, rockable twister elements carried in the spaces between the brackets, fixtures on the rockable elements to clamp portions of a crank shaft blank to be twisted, certain of said brackets carrying stationary fixtures to clamp other portions of the blank, means comprising tracks and rollers for carrying the rockable elements between the 20 brackets and for holding said elements for movement about fixed, aligned axes, and means for rocking the rockable twister elements.

9. A crank shaft twister comprising, in combination, a base, a plurality of upright brackets 25 carried on the base in spaced relationship, rockable twister elements carried in the spaces between the brackets, fixtures on the rockable elements to clamp portions of a crank shaft blank to be twisted, certain of said brackets carrying 30 stationary fixtures to clamp other portions of the blank, means comprising substantially half-circle tracks and rollers therein for carrying the rockable elements between the brackets and for holding said elements for movement about fixed, 35 aligned axes, and reciprocatory means connected with the rocker elements for operating the same.

10. A machine for twisting a crank shaft for six cylinder engines, comprising, in combination, a base, four upright spaced brackets mounted on 40 the base providing two end spaces and one intermediate space, end rockable twister elements in the end spaces including clamp fixtures for holding crank portions of the shaft to be twisted, an intermediate rockable twister element in the 45 intermediate space including a duplex clamp fixture for holding two crank portions of the shaft to be twisted, non-twisting clamp fixtures carried on the two intermediate brackets for clamping two other crank portions of the shaft, means for 50 holding the rockable twister elements for turning movement about aligned axes, said means comprising rollers carried by the brackets and arranged in substantially half-circle tracks formed between adjacent faces of the brackets and the 55 elements, pitmen pivotally connected to the end elements for rocking them together in one direction, and a pitman pivotally connected to the intermediate element for simultaneously rocking the same in the opposite direction.

11. A crank shaft forming machine comprising a stationary die and a movable die, the dies being recessed to receive a crank shaft portion and at least one of said dies including a separable part to so clamp said portion, means on one die co-65 operating with means on the other for operatively supporting the movable die on the stationary die for movement thereon in an arcuate path.
